UNITED STATES PATENT OFFICE.

JOHN MARCHE LYITLE, OF BALTIMORE, MARYLAND.

SWITCH-OPERATING DEVICE.

1,133,730.

Specification of Letters Patent. Patented Mar. 30, 1915.

Application filed May 21, 1912. Serial No. 693,768.

To all whom it may concern:

Be it known that I, JOHN MARCHE LYITLE, of the city of Baltimore and State of Maryland, have invented a new and useful Improvement in Switch-Operating Devices, of which the following is a specification.

My invention relates to improvements in switch operating devices, and it consists in the construction, combination, and arrangement of parts hereinafter fully described and claimed, and illustrated in the accompanying drawing, wherein—

Figure 1 is a top plan view of the switch operating device constructed in accordance with my invention, Fig. 2 is a transverse sectional view taken on the vertical plane indicated by line 2—2 of Fig. 1 and looking in the direction of the arrow, and Fig. 3 is a longitudinal sectional view taken on the vertical plane indicated by the line 3—3 of Fig. 2 and looking in the direction of the arrow.

Referring to the drawings by reference letters, G designates the ties, F the rails, and F' the point of a railway switch of the usual construction.

My switch operating device comprises a bar E, which is mounted upon one of the ties G for a sliding movement transversely of the switch. The bar E is pivotally secured to the point F' as at E' so that one movement of the bar will open the point and another movement close the point. The bar E is adapted to be operated by a pair of levers. Each lever comprises end pieces A which are transversely disposed and which are pivotally mounted upon the longitudinally disposed rods E², and the longitudinally disposed bars B which connect the end pieces A. The levers are pivotally connected to the bar E as at B. This pivotal connection is such that when one of the levers is depressed the point F' is closed and the other lever elevated, and when the other lever is

depressed the point F' is opened and the first lever elevated. The levers may be operated so as to open or close the point F' from the car by any instrument of a well-known or appropriate construction, it only being necessary to exert a downward pressure through the medium of the instrument on one of the bars B of the lever to be operated. The rods E² are secured in a pair of ties G and are held in place by the nuts C.

The switch operating device is protected by a plate T which is provided with a pair of elongated and longitudinally extending slots T', said slots permitting access to the bar B of each of the levers.

It should be apparent from the above description taken in connection with the accompanying drawings, that I provide a switch operating device which is simple, durable, and efficient, and which may be used in connection with any switch structure of well-known form, and which may be installed and maintained at a comparatively low cost.

Having thus described my invention what I claim and desire to secure by Letters-Patent is:

In combination with a switch point, a slidably mounted bar pivotally connected to the point, said bar being disposed transversely of the railway, a pair of rods disposed longitudinally of the railway and secured to the ties, a pair of levers pivotally mounted upon the rods and pivotally connected to the bar, each of said levers comprising transversely disposed end pieces and longitudinally disposed bars connecting the end pieces, and a slotted plate disposed above the bars, rods, and levers.

JOHN MARCHE LYITLE.
